Machinery Corporation, Paterson, N. J., a cor-
poration of New Jersey

Application December 16, 1935, Serial No. 54,607
In Great Britain December 28, 1934

10 Claims. (Cl. 12—31)

The present invention is concerned with improvements in coating-applying machines. The expression "coating-applying machine," as used herein, is intended to be interpreted broadly as including any apparatus or device appropriated to the delivery of a coating-liquid, either one of a readily fluent nature or one which is more viscous, to a work-piece. It is to be understood that features of the invention may find applicability in power-driven apparatus or in non-driven apparatus. The invention will be described herein by way of illustration with particular reference to a machine organized for applying ink or stain to the edges of the breast-covering flaps of shoe-heels.

It is sometimes desired that the edges of heel-breast-flaps shall project slightly beyond the side faces of the heels, and that the edges shall be rounded or otherwise shaped after they have been trimmed, they being known in the trade as Viennese edges. After trimming, the edges of the flap at either side of the heel may be finished on a machine having an oscillating tool with a flap-edge-engaging groove of the desired shape. In producing Viennese edges in the manner mentioned, it is customary to apply ink or stain to the edges of the flap left by the trimming operation to give them the desired color. Hitherto, this has commonly been performed by manual application of the coloring fluid by an operator with a brush or the like, and as it is usually required that the application shall be limited to the flap-edges alone, it will be recognized that the operation has been one calling for considerable care and skill on the part of the operator and, in consequence, has been a time-consuming one.

It is one of the various objects of the present invention to provide a coating-applying machine particularly adapted for performing the operation of applying a coloring fluid to Viennese edges of the breast-flaps of heels, whereby the operation may be carried out with precision and much more rapidly than when performed manually.

By way of example, there is hereinafter described in detail an illustrative coating-applying machine in accordance with the invention, in which machine the several features of the invention are embodied in convenient forms. This illustrative machine comprises, as a feature of the invention, a container or reservoir in which a supply of ink, stain or other coating material is received, a coating-applying tool or device, a tube having a passage for delivering the coating

fluid from the container to the tool and a valve for controlling flow of the fluid to the tool. The applying tool preferably comprises an applying roll to the periphery of which the fluid is delivered and in which is a groove to adapt it to apply the fluid to the angled surfaces formed at the edges of a flap by the trimming operation. The roll is shown as rotatably mounted in a slot in a carrying member, an inclined projecting end part of which member, adjacent to the 10 grooved applying roll, furnishes a surface at the applying locality adapted to serve to guide the margin of the breast-surface of the flap into a position where the edge thereof will enter the groove of the applying roll during the applying 15 operation. Further, the machine includes a valve for controlling flow of the fluid through the tube from the container to the tool.

With different kinds of work which may be met with in a shoe-factory, it may be desired 20 to apply coating-fluids of different colors or other characteristics to flap-edges on different shoes. It will be realized that it would be a time-consuming matter if, when the change of coating-fluid being employed was to be made, the 25 operator had to drain the fluid from the machine and replace it by another fluid. To avoid such disadvantage in the illustrative machine, there is disclosed another feature of the invention, in accordance with which the fluid-container, the 30 coating-applying tool and the tube for delivering coating-fluid from the container to the tool are constructed as a unit. A plurality of such units may be provided and when it is desired to change from one coating-fluid to another, the 35 unit containing the coating-fluid that has previously been used may be detached readily from supporting means therefor on the machine and replaced by a unit containing the different coating-fluid that is desired to use. The machine 40 has also means operative to effect actuation of the valve of whichever unit is in operative position.

Inks or stains designed for application to shoe-part-edges on which a setting operation 45 is subsequently to be performed, commonly include a certain amount of material of a waxy nature in their composition, as this is helpful in securing the desired well-finished appearance after setting. Such wax-containing fluids 50 are consequently of a somewhat viscous nature, and, when used in the illustrative machine hereinafter described, we have found that they are liable to clog or choke the passages or apertures through which they flow, unless precautions are 55

taken to the contrary. As a further feature of the invention we communicate an oscillatory or vibratory movement to the fluid-container of the machine, the tube leading therefrom and the applying device. By this means the fluid is so agitated that little or no clogging will be experienced.

The various objects and features of the invention will be made clear by the following detailed description, given with reference to the accompanying drawing, of the illustrative machine.

In the drawing,

Fig. 1 is a side elevation of the illustrative machine;

Fig. 2 is an enlarged view, chiefly in section in a plane at right-angles to Fig. 1, of the coating-applying parts and supply-reservoir;

Fig. 3 is an enlarged detail view in side elevation of a coating-applying tool of the machine, this figure also showing a work-piece being operated upon;

Fig. 4 is a horizontal section, but on a larger scale, through the clamp for a removable tool and reservoir unit, and

Fig. 5 is a plan view of the tool-oscillating mechanism shown in Fig. 1.

The machine comprises a tubular member 101, which extends substantially vertically, and carries at its upper end a container or reservoir 103 for the fluid coating-material and at the lower end a coating-applying tool 105. The tubular member 101 is embraced by a yoke 107 formed at one end of a horizontal rod or spindle 109, a clamping screw 111 holding the member 101 securely in the yoke. The arrangement is such that on loosening the screw 111, the member 101 and the parts carried thereby can readily be removed as a unit from the yoke. A collar 110 surrounds the member 101 and is held in fixed position thereon by a set-screw 112. As seen in Fig. 2, when the member 101 is in proper position in the yoke 107, the collar 110 engages the upper surface of the yoke. The machine is conveniently provided with a number of units comprising a tubular member 101, a reservoir 103 and an applying tool 105, the different units serving to supply fluid coating-materials of different kinds or colors. The arrangement described is such that on loosening the screw 111, any one unit can be removed from the yoke 107 and another of the units substituted for it, each being readily positioned heightwise when placed in the yoke by the engagement of the collar 110 with the upper surface of the yoke. It will be appreciated from the description which hereinafter follows, that a unit should be properly located vertically in order that means for causing delivery of the coating material from the unit may co-operate suitably with said unit. The machine is conveniently provided with a bracket (not shown) upon which units not actually in use may be supported, with their tubular members 101 vertical and with the tools 105 dipping into a bath 65 of water. This will tend to reduce any tendency of the applying tools to clog when not in use.

The rod 109 is housed in a sleeve 113 projecting horizontally from a casing 115 supported on a pedestal 116, into the interior of which casing 70 the rod 109 projects. Within the casing is mechanism M for imparting a rapid oscillatory movement of very small amplitude to the rod. For example, this mechanism may be of the same nature as that disclosed in Letters Patent of the 75 United States No. 1,982,740, Keall et al., Decem-

ber 4, 1934, and will comprise a block 244 within the casing 115 secured on one side to the end of the rod 109 and on the other side to the short shaft 246 in alinement with the rod 109 and, like it, journaled in the casing. Within this block 5 244 is a swivel member 248 providing a horizontal bearing 250 continued through sleeve-like extensions 251 (Fig. 5). In this bearing 250 is journaled a wobble shaft 252 formed integrally with a drive shaft 254 on which is mounted a pulley 10 256 to which power may be supplied from a suitable source. As the drive shaft is rotated, this wobble shaft 252 imparts a movement to the swivel member 248 which may be resolved into 15 two components. The first component, in a horizontal plane, imparts an oscillatory movement to the swivel member 248 which has no effect on the rod 109. The other component, in a vertical plane, acting through the swivel member 248, the block 244 and the rod 109, imparts an oscillatory 20 movement to the latter and to the tool 105 carried thereon. The amplitude of the oscillatory movement of the rod is preferably so small that the tool 105 does not move to and fro during the oscillation through more than about $\frac{1}{2}$ of an 25 inch.

The reservoir 103 may be in the form of a cylindrical glass vessel 117 closed at the top and at the bottom by plates 119, 121, respectively. Both plates are centrally bored to receive a portion 123 of reduced diameter of the member 101. This portion 123 extends axially through the reservoir and is threaded at its upper end to receive a nut 125. The lower plate 121 rests upon a step 127 on the member 101 and the arrangement is such that on tightening the nut 125 the parts of the reservoir are clamped firmly together. Two apertures 118 (Fig. 2) are provided in the upper plate 119 through one of which liquid may be introduced as required into the 40 reservoir.

At its lower end, the tubular member has an extension-piece 139 of reduced diameter threaded thereon. The applying tool 105 comprises a metal roll 128 of small thickness, of which all except 45 its extreme lower portion is received in a slot 130 in a lower solid end of a sleeve member 133 surrounding the extension of the tubular member 101. The roll 128 is rotatable about a pin 132 which extends across the slot. The axis of the 50 roll is substantially horizontal. As best seen in Fig. 3, the edge-surface of the roll is V-grooved. The sleeve member 133 is so formed that the general plane of its lower surface makes an angle of about 30° with the vertical axis of the tubular member 101 and is curved transversely, the downwardly projecting end providing a surface 134, which is adapted to aid in positioning a workpiece being presented to the roll 128. The upper portion of the sleeve member 133 is received upon the extension-piece 139, and to maintain the sleeve member securely in place, it has two ears 136 extending laterally therefrom and receiving between them the lower end of a rod 138. At its upper end, this rod is rigidly secured to a split collar 140 clamped on to the member 101 by a screw 142. The lower end-portion of the rod 138 has a hole formed therethrough and a threaded pin 144 passes through registering holes in the ears 136 and through the hole in the 60 rod, the hole in one of the ears being screw-threaded so that the pin is maintained in place. The pin, however, is readily removable should it be desired to take off the tool 105 for cleaning or other purposes. Further, in cases where the ma- 65

70 75 80 85 90 95 100 105 110 115 120 125 130 135 140 145 150

chine may be called upon to operate upon work of different thicknesses, it may be convenient to provide a number of replaceable tools 105 which have rolls 128 of different thicknesses.

The means for controlling the supply of coating-material from the reservoir to the tool will now be described. Slidably received in the axial bore of the member 101 is a valve-rod 157. The member has near the bottom of the reservoir, apertures 159 through which liquid from the reservoir may pass into the central passageway in the member. Liquid so leaving the reservoir may flow down the passageway, since the latter below this point is at all places of somewhat larger diameter than the valve-rod 157 which is received in it. The lower portion of the valve-rod is received in a bore in the upper portion of the extension-piece 139. Normally, when it is not desired that liquid should be delivered to the tool 105, the extreme lower end of the rod, which is provided with a conical surface 163, bears against a conical seat in the extension-piece and thus prevents discharge therefrom. But, when the valve-rod is raised, liquid can flow past the lower end into a constricted passage 169 in the lower portion of the extension-piece. Liquid passing through the passageway is received in the interior of the sleeve member 133. An aperture 173 is provided in the lower portion of the sleeve member through which the liquid finally passes, to drip upon the upper portion of the roll 128.

For controlling the position of the valve-rod 157, the following arrangement is provided. Extending laterally from the reservoir-plate 119 is an arm 146, and extending upwardly from this arm is a short pillar 148. The pillar is bifurcated at its upper end, and pivoted to it between the bifurcations is one end of a lever 150, the other extremity of which is pivoted to a bifurcated head 152 formed at the upper end of the valve-rod 157. The connection between the lever 150 and the head 152 comprises a removable pin, which may be taken out if it is desired to remove the valve-rod 157 for cleaning. A tension-spring 154, connected at its upper end to the lever 150 and at its lower end to a pin 156 on the split collar 148, normally serves to urge the valve-rod downwardly and so, by maintaining the conical surface 163 against its seat, prevent delivery of coating liquid from the reservoir 103 to the applying tool 105.

Extending upwardly from the yoke 107 is a pillar 158, which is bifurcated at its upper end and has pivoted to it at 160, between the bifurcations, a lever 162. The lever in front of the pivot has formed on it a step 164, which underlies and is in contact or almost in contact with a step on the head 152 of the valve-rod. The lever also extends rearwardly from its pivot and is loosely joined by a pin 166 to an eye at the upper end of a rod 168 connected at its lower end to a treadle, not shown. The distance between the pin 166 and the pivot 160 is several times that between the pivot 160 and the head 152, so that a small upward movement is communicated to the end of the lever adjacent the head by a considerably larger downward movement of the end of the lever at the pin. The treadle-rod 168 passes through alined apertures in two fixed brackets 170 and 172. Surrounding the rod 168 between the upper surface of the bracket 170 and a collar 174 fixed to the rod is a compression-spring 176, which normally serves to urge the rod upwardly into a position in which another fixed collar 178 on the rod engages the lower surface of the

bracket 170. The extent to which the rod 168 may be moved downwardly, and thus the extent to which the valve-rod 157 may be lifted off its seat, is determined by the engagement of yet another collar 180 fixed to the rod, with the upper end of a tubular screw 182 threaded into the bracket 172 and through which screw the rod passes. The extent to which the rod 168 may be moved downwardly upon depression of the treadle may be adjusted by turning the screw. The collar 110 so determines the heightwise position of the unit comprising the member 101, the reservoir 103, the tool 105 and associated parts in the yoke 107, that the step on the head 152 of any applied unit will be located in the correct relation to the step 164 on the lever 162.

In the use of the machine to apply an ink or stain to a Viennese edge projecting from a flap F on an attached heel H, after the side edges of the flap have been trimmed to form an angular edge, the work is presented to the tool 105 in the manner indicated in Fig. 3. The angled surfaces of the flap-edge bear against the sides of the V-groove in the periphery of the roll 128. The inclined end surface 134 will contact with the front marginal face of the flap and will assist in bringing the work into proper relation to the roll. As the operator thus applies the work to the tool, he will simultaneously depress the treadle to raise the valve-rod 157 and allow liquid to flow to the roll through the passageway 169 and aperture 173. The arrangement described permits the operator very accurately to control the amount of fluid supplied to the roll. The diameters of the passageway and the aperture are so small as to prevent a large excess of fluid ever being delivered to the roll 128, and the operator can at any time cut off the supply by permitting the spring 175 to raise the treadle-rod. Once fluid is delivered to the roll, as the operator advances the work, said roll will be rotated by frictional contact and will be effective to apply the desired coating to the flap-edge. One edge of the flap having been operated upon, the shoe will be turned over and the edge at the other side of the flap colored in similar fashion. It has been found that the apparatus described enables the coloring to be carried out with a rapidity and precision greatly in advance of what was possible when the operation was performed manually. From consideration of Fig. 3, it will be appreciated that the inclined shape of the upper portion of the lower surface of the sleeve member 133 makes it unlikely that the covering at the side of the heel will at any time be brought into contact therewith and thus undesirably marked with the coating material. Should any coating material be accidentally applied to the marginal portion of the breast-surface of the flap, this is not particularly disadvantageous, since in any case it is probable that this surface of the flap will be subjected to a scouring operation, which, incidentally, will remove any of the coating therefrom.

As has hereinbefore been described, when the machine is in operation, the rod 168 will be rapidly oscillated so that a vibratory motion is communicated to all the parts carried on the rod. The vibratory movement of the roll 128 is of such small amplitude that it does not interfere with, and may even assist, its applying function. On the other hand, the agitation which the vibration imparts to the fluid in the apparatus greatly reduces any tendency which there may be towards choking or clogging, such as

would cause an uneven delivery to the roll. Inks or stains designed for application to shoe-part edges on which a setting operation is subsequently to be performed commonly include a certain amount of material of a waxy nature in their composition. Such inks or stains are liable to clog passages or apertures through which they flow, unless precautions are taken to the contrary. It is not, however, regarded as by any means essential that the machine should be provided with oscillating mechanism. Certain inks or stains may be found to flow quite freely without any oscillatory motion being imparted. In such event, the reservoir, tool and associated parts may merely be supported upon a stationary bracket and the oscillating mechanism omitted entirely from the machine with a consequent lowering of the cost.

Having described our invention, what we claim as new and desire to secure by Letters Patent of the United States is:

1. A fluid-applying machine comprising a support, a tube carried thereby and provided at its delivery-end with a slot and with a constricted passage leading into the slot at one extremity and having about the opposite extremity a valve-seat, a valve movable through the tube and co-operating with the seat, and a peripherally grooved roll rotatable in the slot.

2. A fluid-applying machine comprising a support, a tube carried thereby, an applying tool separably mounted upon the delivery-end of the tube, a rod secured to the tube and extending into co-operation with the tool, and a removable pin engaging the tool and rod.

3. A fluid-applying device comprising a tube having its delivery-end inclined with respect to its axis and being provided with a slot, and an applying roll rotatable in the slot, the portion of the inclined end projecting beyond the slot being adapted to receive contact of the work to guide it toward the roll as the work is brought into engagement with said tool.

4. A fluid-applying device comprising a tube supported in depending position and having its delivery-end inclined with respect to its axis and being provided with a slot, and an applying roll rotatable in the slot, said roll projecting beyond the upwardly inclined surface at one side of the slot and lying within the downwardly inclined surface at the opposite side of said slot.

5. A fluid-applying device having a removable unit comprising a tube provided with an opening

in its wall, a fluid-container surrounding one end of the tube and delivering through the opening therein, means engaging the tube for holding the container thereon, an applying tool rotatably mounted upon the end of the tube opposite the container, and a valve-rod extending through the container and tube and controlling the flow of liquid to the tool.

6. A fluid-applying machine comprising a spindle, a yoke at one end thereof, a tube separably clamped by the yoke, a fluid-container carried by the tube at one side of the yoke, and an applying tool mounted upon the tube at the opposite side of the yoke.

7. In a fluid-applying machine, a support, a spindle carried by the support, a yoke at one end of the spindle, a tube separably clamped by the yoke, a fluid-container carried by the tube at one side of the yoke, an applying tool mounted upon the tube at the opposite side of the yoke, a valve-rod extending through the container and tube and controlling the delivery of fluid to the tool, and an actuating member movable upon the support and acting on the valve-rod outside the container.

8. In a fluid-applying machine, a support, a spindle carried by the support, a yoke at one end of the spindle, a tube separably clamped by the yoke, a fluid-container carried by the tube at one side of the yoke, an applying tool mounted upon the tube at the opposite side of the yoke, a valve-rod extending through the container and tube and controlling the delivery of fluid to the tool, a spring connecting the valve-rod and tube and serving normally to prevent delivery to the tool, and a lever fulcrumed upon the support and acting upon the valve-rod to cause delivery.

9. In a fluid-applying machine, a support, a fluid-container, an applying device interconnect- ed with said container to be supplied therefrom, said container and applying device being movable together upon the support, and means for producing oscillation of the container and the applying device.

10. In a fluid-applying machine, a support, a spindle movable in the support, a tube secured to the spindle, a fluid-container and applying device mounted upon the tube and connected thereby for the passage of fluid from the container to the applying device, and means for oscillating the spindle.
